FIG. 1

FIG. 2

FIG. 3

FIG. 1 is a top view of the jigger, showing our new design.

FIG. 2 is a side view of the jigger, the opposite side appearing the same, the jigger being a symmetrical device providing four different vessels of the same size, any three of which serve as a base, the fourth of which serves as a measuring vessel.

FIG. 3 is a bottom view of the jigger.

We claim:

The ornamental design for a jigger, substantially as shown and described.
